OIL BURNER

Leslie W. Holmes, Stratford, Conn., assignor to
 Croneque Oil Burner Corporation, New York,
 N. Y., a corporation of Delaware

Application October 24, 1930, Serial No. 490,921

14 Claims. (Cl. 158—86)

This invention relates to oil burners, and more particularly, to means for mounting the same in the ash pit or base of a stove or heater respectively.

5 In oil burners of this type where a single burner unit is used, it is usually a simple matter to place the burner in the desired position in the stove or heater for use and to adjust it vertically for height. However, when two or more burner units 10 are desired, it is frequently difficult to place the several units in the desired positions in the stove, except where the burners need to be adjusted toward or from each other in a straight line a limited extent, which has been provided for by 15 the prior art by having horizontal arms on the supporting standard with slots to receive bolts passing through the burner units.

An object of the present invention is to provide a mounting for a plurality of burner units where- 20 by the units may be universally adjusted in a horizontal plane individually, and collectively adjusted vertically so that the several burners may be placed in any position at all in a common horizontal plane.

25 This is accomplished by the structure shown in the accompanying drawings, in which—

Figure 1 is an elevation of the support of the present invention, showing the burners in the positions which they occupy when adjusted in a 30 line perpendicular to the front or back of the stove.

Fig. 2 is a plan view of the supporting means and the base portions of the burner units, showing the burner units located at different distances 35 toward and from a wall of the stove, and showing in dot-and-dash lines another possible position of the burners in which they are located closer together than in either Fig. 1 or in full lines in this figure.

40 Fig. 3 is a plan view of the spider on which the supporting standard is mounted.

Fig. 4 is a plan view similar to Fig. 2, but showing the burners adjusted toward the front or back wall of the fire box.

45 Fig. 5 is a view similar to Figs. 2 and 4, but showing two of the burner units located as far apart from each other as possible with a third unit interposed between them.

Fig. 6 is a plan view of a modification of this 50 invention.

Fig. 7 is an elevation of a portion of the stand- 55 ard or vertical support on which the burner-carrying arms are directly mounted.

Fig. 8 is a plan view of another modification of this invention, wherein rows of holes are sub-

stituted for the adjusting slots in the burner base and its carrying arm.

Fig. 9 is an elevation showing the burner base and its carrying arm partly in section, and showing a coupling pin substituted for the bolt used in the other forms of the invention for supporting the burner base on the arm in any of the possible adjusted positions, and also showing a modified form of mounting for the burner-carrying arm on the vertical support. 10

Fig. 10 is a detail view showing a further modification of the means for mounting the carrying arm on the vertical support.

The burner units 10 may be of any usual, suitable, or desirable form and construction, and accordingly, the drawing shows a conventional form of burner. When only one burner 10 is needed in a stove or heater, it may, with convenience, be located at any desired place in the ash pit of the stove. However, frequently it is desired to have a plurality of burners and these usually are placed directly beneath the stove-holes so that the heat rising from the burner units may impinge upon a cooking utensil located over the stove-hole. The stove-holes are variously ar- 25 ranged in different stoves and heaters and thus a large variety of standards or supports would be needed to mount the burner units in the desired positions. This difficulty has been partially overcome heretofore by providing the standard with a 30 pair of oppositely directed arms, each of which has a slot to receive a bolt to fasten the burner unit to the standard in various positions in a horizontal plane and in a straight line extending from the front to the back of the stove. 35

However, there are many cases where this simple adjustment would not suffice, and accordingly, the present invention provides a universal mounting for the burners in a horizontal plane and for adjusting the mounting means so that the burn- 40 ers may be adjusted in common vertically.

Accordingly, in the device of the present invention, a standard 11 which is supported at its lower end by a spider 12 has slidably mounted on its upper end a head 13 which is located in the de- 45 sired vertical position on the standard 11 by a set-screw 14. The head 13 has a plurality of radially extending arms 15, each of which has a hole 16 near its ends. The arms preferably extend at right-angles to each other and usually only the 50 opposite arms 15 are utilized, as shown in Figs. 2 and 4. Each arm 15 may be pivotally connected to an extension arm 17 by a bolt 18 passing through the hole 16 in the arm 15, and since these extension arms 17 carry the burner units 10, by 55

rotating the extension arms 17 about the bolt 18, the positions of the burner units 10 may be varied to move them closer to or farther from a wall 19 of the fire box which extends from the front to the back of the stove. Thus, as shown in Fig. 2, the left-hand burner unit 10 may be arranged farther from the wall 19 than the right-hand burner unit 10, and of course, it will be understood that the burner units may be swung individually about the axis of their bolts 18 to any desired position. For instance, the extension arms 17 may form a straight angle as shown in Figs. 1 and 4.

To permit the burner units 10 to be adjusted toward and from each other, either when the extension arms 17 are located in a straight line as shown in Fig. 4, or when they are angularly disposed as shown in Fig. 2, each extension arm 17 is provided with an elongated slot 20 through which a bolt 21 connected to a base 22 of a burner unit 10 extends. Thus, by loosening the bolt 21, the unit with the bolt may be slid from a position where the bolt is located near the end of the arm 17 as shown in full-lines in Fig. 2, to a position where the bolt is located near the inner end of the slot 20 and close to the bolt 18 on which the extension arm 17 is pivotally mounted, as shown in dot-and-dash lines in Fig. 2. Of course, each burner unit 10 is separately adjustable along the slotted extension arm 17 and if desired one unit 10, for instance the right-hand unit in Fig. 4, may be located with its bolt 21 near the outside end of the slot 20, while the other unit 10 may have its bolt 21 located near the inner end of the slot 20 of the other arm, thereby moving the units closer to the front or back wall 23 of the stove.

To permit a further separation or closer juxtapositioning of the units 10 than would be permitted by the slots 20 in the arms 17 and for other purposes, the base 22 of each unit may, and preferably is, provided with an elongated slot 24 through which the bolt 21 extends and along which slot the unit may be adjusted with relation to the bolt.

For instance, as shown in Fig. 5, the units 10 may each have its bolt 21 located at the end of its slot 24 while the bolt 21 is located at the end of the slot 20 in the extension arm 17, thus permitting the burner units 10 to lie as far apart as the supporting devices will permit, or the bolt 21 may be located mid-way between the ends of the slot 24 as shown in Fig. 2, or at any intermediate position. The slots 24 may also be utilized to move the burner units 10 toward or from the wall 19 which extends from the front of the stove to the back without necessitating the adjustment of the extension arms 17, as shown in Fig. 4, if desired.

Of course, as many of the radially disposed arms 15 as desired may be provided with extension arms 17, depending upon the number of burner units 10 needed. For instance, as shown in Fig. 5, three extension arms 17 are employed because there are three units 10. In this arrangement of the invention, the central burner unit 10 may be located between the other two which are spread far apart by reason of the bolt 21 being at the ends of the slots 20 and 24, and for the same reason the central unit may be located close to a line running through the centers of the two other units.

The spider 12 on which the standard 11 is supported, is provided with a plurality of slots 25 through which bolts 26 serving to hold the spider

to the floor 27 of the ash pit may extend, the burner being brought to proper level by adjusting screws 28 carried by the ends of the spider arms 29.

In case the supporting member of the oil burner merely rests on the bottom 27 of the ash pit instead of being secured thereto in fixed position as shown in Fig. 1, under which circumstance it may be bodily adjusted in the ash pit, one of the arms, for instance the arm 17a, Fig. 6, may be rigidly secured to, or form part of, the head 13, while the other arm 17 may be pivoted on the bolt 18 and have a longitudinal slot 20 engaged by the bolt 21 which also passes through the diametrical slot 24 in the burner base 22 carried by the pivoted arm 17. Thus, to adjust the burners relative to each other, only the burner unit carried by the pivoted arm 17 need be adjusted, for the supporting standard and its spider may be moved bodily to move the other burner relative to the walls of the fire box. The fixed arm 17a may have a longitudinally disposed slot 20a for the purpose of permitting the burners to be moved farther apart than would be permitted if only the pivoted arm 17c were provided with the longitudinal slot 20.

Within the scope of this invention, the head 13 may, of course, be omitted entirely as shown in Fig. 7, in which the pivoted arms 17b directly engage the standard 11 and have set-screws 30 30 by means of which they are held in the position to which they may be adjusted about the standard 11. In this case, the arms 17b may be held in desired vertical position while being adjusted horizontally by a pair of adjustable collars 31 35 fixed to the standard 11 by set-screws 32.

This invention is not limited to the provision of slots in the arms 17 and in the bases 22 of the burners for permitting the adjustment referred to, but other adjustable connections may be employed, such, for instance, as shown in Fig. 8, in which each arm 17c is provided with a longitudinally extending row of holes 33 and the web of the burner base is provided with a diametrical row of holes 34 for receiving the bolt 21 by means of which the base of the burner is held in desired position on the arm and at several places along the arm. This is accomplished by placing the burner in the desired position and then shifting the burner until one of its holds 34 aligns with the nearest hole 33 on the arm 17c. When this arrangement is made, a stud or pin 35, as shown in Fig. 9, may be substituted for the bolt in some cases.

It is also within the scope of this invention to merely rotatably support one or more of the burner-supporting arms instead of both rotatably supporting and securing the arm, as shown in Figs. 1 to 5. Such an arrangement is illustrated in Fig. 9, wherein the head 13 is provided with studs 36 fitting holes 37 in the burner-carrying arms 17d and, of course, this arrangement may be reversed as shown in Fig. 10, wherein the arm 17e has a stud 38 fitting a hole 39 in the head 13.

Variations and modifications may be made within the scope of this invention and portions of the improvements may be used without others.

Having thus described the invention, what is claimed as new and for which it is desired to obtain Letters Patent, is:—

1. In an oil burner having a plurality of burner units, a standard adapted to be secured on a supporting surface; a head mounted on said standard common to said plurality of burner

units; a plurality of arms extending outwardly from said head, one for each burner, each of said arms having an elongated slot extending longitudinally thereof; means engaging said slot at any point therealong for adjustably securing a burner unit to the arm in desired position; and means for pivotally mounting each arm on said head and permitting adjustment of the burner units rotatably about the standard.

2. In an oil burner having a plurality of burner units, a standard adapted to be secured on a supporting surface; a head mounted on said standard common to said plurality of burner units; a plurality of arms extending outwardly from said head, one for each burner, each of said arms having an elongated slot extending longitudinally thereof; a base for each burner unit having an elongated slot extending diametrically thereof; and means adjustably located in the diametrical slot in each burner base and adjustably located in the elongated slot of the arm carrying said burner unit for securing the latter and its arm in adjusted position.

3. In an oil burner having a plurality of burner units, a standard adapted to be secured on a supporting surface; a head mounted on said standard common to said plurality of burner units; a plurality of arms extending outwardly from said head, one for each burner, each of said arms having an elongated slot extending longitudinally thereof; a base for each burner unit having an elongated slot extending diametrically thereof; means adjustably located in the diametrical slot in each burner base and adjustably located in the elongated slot of the arm carrying said burner unit for securing the latter and its arm in adjusted position; and means for pivotally mounting each of said arms on said head and permitting adjustment of the burner units rotatably about the standard.

4. In an oil burner having a plurality of burner units, a standard adapted to be secured on a supporting surface; a head mounted on said standard common to said plurality of burner units; a plurality of arms extending outwardly from said head, one for each burner, each of said arms having an elongated slot extending longitudinally thereof; a base for each burner unit having an elongated slot extending diametrically thereof; means adjustably located in the diametrical slot in each burner base and adjustably located in the elongated slot of the arm carrying said burner unit for securing the latter and its arm in adjusted position; means for pivotally mounting each of said arms on said head and permitting adjustment of the burner units rotatably about the standard; and means for adjusting the head, the arms and burner units supported thereby vertically on the standard.

5. In an oil burner, a plurality of burner units; a vertical support common to said units; means for securing said support to the floor of a fire-box in a stove in fixed position; a plurality of horizontal arms each carrying one of said burner units; and means for securing the arms to the vertical support and permitting adjustment of the arms and the burner units carried thereby rotatably in a horizontal plane relative to each other and to the vertical support to locate the burners in desired position relative to the walls and top of the stove.

6. In an oil burner, a pair of burner units; a vertical support common to said burner units; means for mounting said support on the floor of a fire-box in a stove in fixed position; and

means for supporting said burner units on said vertical support including a horizontal arm secured to one of said burner units and rotatably mounted on the vertical support for movement with the burner unit which it carries in a horizontal plane relative to the vertical support and the other burner unit supported thereby.

7. In an oil burner, a pair of burner units; a vertical support common to said units; means for mounting said support on the floor of a fire-box in a stove in fixed position; and means for supporting said burner units on said vertical support including a horizontal arm carrying one of said burner units and rotatably mounted on the vertical support for movement with the burner unit which it carries in a horizontal plane relative to the vertical support and the other burner unit, and means for adjustably securing the burner unit carried by said horizontal arm relative thereto to permit adjustment of the last-mentioned burner unit toward and from the vertical support and the other burner units supported thereby.

8. In an oil burner, a plurality of burner units; a vertical support common to said units; and means for supporting said burner units on said vertical support including a horizontal arm carrying one of said burner units and rotatably mounted on the vertical support for movement with the burner unit which it carries in a horizontal plane relative to the vertical support and the other burner unit, and means including a bolt engaging the burner unit and a longitudinally extending slot in said horizontal arm for adjustably securing the burner unit carried by said horizontal arm relative thereto to permit adjustment of the last-mentioned burner unit toward and from the vertical support and the other burner units supported thereby.

9. In an oil burner, a plurality of burner units; a vertical support common to said units; and means for supporting said burner units on said vertical support including a horizontal arm carrying one of said burner units and rotatably mounted on the vertical support for movement with the burner unit which it carries in a horizontal plane relative to the vertical support and the other burner unit, and means including a bolt and a diametrically disposed slot in the base of the burner unit carried by said horizontal arm for adjustably securing the latter thereto and permitting its adjustment bodily and rotatably with relation to the said horizontal arm.

10. In an oil burner, a pair of burner units; a vertical support common to said units; and means for supporting said burner units on said vertical support including a horizontal arm carrying one of said burner units and rotatably mounted on the vertical support for movement with the burner unit which it carries in a horizontal plane relative to the vertical support and the other burner unit, a slot diametrically disposed in the base of the burner unit carried by the said horizontal arm, a longitudinally extending slot in the latter, and a bolt passing through said slots for adjustably securing the burner unit carried by said horizontal arm relative thereto to permit adjustment of the last-mentioned burner unit toward and from the vertical support and the other burner units supported thereby and bodily and rotatably with relation to the horizontal arm on which the said adjustable unit is carried.

11. In an oil burner, a pair of burner units; a vertical support common to said units; and

means for securing said burner units to said support for adjustment with relation to the other including a diametrically disposed elongated slot in the base of one of said burner units, a horizontally disposed member on the vertical support, and a bolt passing through said slot in the horizontal member for securing the said burner unit to the horizontal member in various positions with relation thereto and to the other burner unit carried by the vertical support.

12. In an oil burner, a pair of burner units; a vertical support common to said units; and means for securing said burner units to said support for adjustment with relation to the other including a diametrically disposed elongated slot in the base of one of said burner units, a horizontally disposed member on the vertical support, an elongated slot in said horizontal member disposed radially of the support, and a bolt passing through said

slots for securing the burner unit to the horizontal member in various positions to which it may be adjusted bodily or radially at various points along the horizontal member relative to the latter and to the other burner unit carried by the support.

13. In an oil burner, a plurality of burner units; a vertical support common thereto having a horizontally disposed member; and means for adjusting said burner units one relative to the other bodily along said horizontal member and bodily with relation to said horizontal member at a point therealong at which it is adjusted.

14. In an oil burner, a plurality of burner units; and means for supporting said units for adjustment toward or from each other along a straight line or arcuate path.

LESLIE W. HOLMES.
